UNITED STATES PATENT OFFICE.

JAMES T. CHURCHILL, OF ST. JOSEPH, MISSOURI.

SUPPORT FOR SWINGING OR PENDENT SCAFFOLDS.

SPECIFICATION forming part of Letters Patent No. 288,977, dated November 27, 1883.

Application filed August 21, 1883. (No model.)

To all whom it may concern:

Be it known that I, JAMES T. CHURCHILL, a citizen of the United States, residing at St. Joseph, in the county of Buchanan and State 5 of Missouri, have invented a new and useful Support for Swinging or Pendent Scaffolds, of which the following is a specification.

The object of my invention is to provide a strong, light, safe, and easily-movable swinging scaffold for the use of carpenters, painters, galvanized-cornice workers, and builders generally. They are hung from cornices or any other projections or supports where the hook can get a firm hold. To place in position for 15 use, two or more of them are drawn up by a rope, or carried up through a building, and hung from a cornice or other support, about twelve or fifteen feet apart. The scaffold-board is placed in position by tying a rope 20 three or four feet from each end of the board and letting the same down at an angle of about forty-five degrees, sliding one end into the bottom of one support, then lowering the other 25 end and moving slightly backward into the other; or place board in position on the ground and draw up supports with ropes. The weight 30 of two supports and a board one and a half inch thick and fourteen feet long will not exceed fifty-five pounds, and is easily moved by one man at each hook sliding it along the 35 cornice. The "support" is designed to be used in pairs by painters, with scaffold-board twelve or fifteen feet long. By cornice-workers and others they should be hung at intervals of twelve or fifteen feet, with scaffold- 40 boards between, forming a scaffold the entire length or width of a structure. I attain my objects by the mechanism illustrated in the accompanying drawings, in which—

Figure 1 represents the support entire. Fig. 2 represents the notched board shown in lower part of Fig. 1. Fig. 3 represents board or slat for raising scaffold-board. Fig. 4 represents

small wooden wedge seen at bottom of Fig. 1. G G G, Fig. 1, is an acute triangular frame 45 constructed of clear straight-grained pine-wood.

A is a flat wrought-iron hook, twisted to strengthen it at top, and is securely bolted to top of frame G G G with two three-eighths-inch 50 iron bolts, as shown.

B B B are wooden steps or "rungs" (set into edge of and secured to frame G G G with heavy screws) to come down from or go up on the roof or other support from which they 55 hang.

CCCC, Fig. 1, are three-eighths-inch round-iron staples secured to frame G G G by clinching. They are used as receptacles for boards 60 shown in Figs. 2 and 3.

D, Fig. 2, is a notched board of hard wood, three and one-half feet long by one inch thick. It is used in the two lower staples C C, Fig. 1, as a rest against the wall to prevent the scaffold from swinging in or outward from the 65 building.

E, Fig. 3, is a hard-wood board, five feet long by one inch thick, used in upper staples C C, Fig. 1, to raise scaffold-board higher when necessary; also, to use in lower staples C C, Fig. 1, to widen scaffold by laying an extra 70 board on each side of center scaffold-board.

F, Fig. 4, is a small wooden wedge to secure notched board D, Fig. 2, to bottom of support, as shown at F in Fig. 1.

75

I claim—

In a pendent scaffold-bracket, the combination, with the triangular frame, of the supporting-hook, the steps, and the staples, and the cross-pieces therefor, all substantially as 80 and for the purpose specified.

JAMES T. CHURCHILL.
